METHOD OF MAKING IMPERVIOUS BAGS

George Arlington Moore, Louisville, Ky., assignor
to Humoco Corporation, Louisville, Ky., a corporation of Delaware

Application May 27, 1936, Serial No. 81,981

3 Claims. (Cl. 93—35)

This invention relates to containers and more particularly to containers comprising fibrous materials and to a method and means for sealing the same.

5 It has been heretofore proposed to seal the ends or seams of containers made of waxed paper by the application of heat and pressure thereto, the wax body being thus rendered effective to hold the adjacent surfaces of the container together. Joints or seams formed in this manner, however, are not impervious to air under all 10 conditions, the joints are always weak as surface tension is relied upon, the seal formed thereby is easily broken, thus necessitating very careful handling. Said wax joints or seams become particularly weak when the package is subjected to merely ordinary room temperatures in hot seasons, thus resulting in the breaking of the package at the joints or seams and loss of the contents thereof.

It has also been proposed to seal packages made of wax impregnated fibrous materials by applying a solvent activatable adhesive to a marginal unwaxed portion of the open end or joints thereof. 25 This method of sealing not only increases the cost and difficulties involved in the manufacture of the bag but, in addition, subjects the contents to contamination during the step of activating said adhesive. Furthermore, it is extremely difficult, if not impossible, to seal a container in this manner and render the same impervious to both air and moisture under all conditions of 30 temperature and humidity. It is also a well-known fact that fibrous materials such as paper or cardboard are weakened bodily when soaked with liquid paraffin or the like or when damped with adhesive activating solvents.

It is accordingly an object of this invention to provide a novel sanitary container made at least 40 in part of fibrous materials which is adapted to be readily sealed and which can be impervious to air and moisture.

Another object is to provide novel means for simultaneously sealing a package and forming a 45 line of severance without impairing the imperviousness of the seal whereby the package may be readily opened for dispensing the contents thereof.

Still another object is to provide a novel and 50 sanitary fibrous package formed from a single blank which is impervious to air and moisture, and a novel method for making same.

A further object is to provide an impervious package of fibrous materials wherein the fibers 55 of the material are not weakened in the process

of manufacture, such as by impregnating the same with paraffin wax.

Another object is to provide a novel bag or container which can be securely closed without the use of string, gum tape, etc.

The above and further objects and novel features of the invention will more fully appear from the following detailed description when taken in connection with the accompanying drawing. It is to be expressly understood, however, that the drawing is for the purpose of illustration only and is not designed as a definition of the limits of the invention, reference being primarily had for this purpose to the appended claims.

In the drawing, wherein like reference characters refer to like parts throughout the several views,

Fig. 1 is an isometric view of one form of package which may be employed in carrying out the 20 present invention, the same being shown with one end open;

Fig. 2 is a similar view showing the container after the open end has been sealed;

Fig. 3 is a side elevation of one form of apparatus which may be used to seal the open end 25 of the package of Fig. 1;

Fig. 4 is a front elevation of said apparatus with parts thereof broken away; and,

Fig. 5 is an enlarged detail view of the sealing 30 heating irons of the device of Fig. 3.

The single embodiment of the invention illustrated is shown, by way of example, as comprising a paper bag 10 of the same type and texture as paper bags commonly employed in grocery 35 stores for packaging bulk foods or the like. Bag 10 is preferably constructed of a single sheet or blank or fibrous material such as paper, folded in any suitable or well-known manner to form a container having at least one end thereof open 40 as seen in Fig. 1. In the form shown, the blank is folded so as to form a container of rectangular cross-section, the ends of the blank being brought into overlapping relation to form a vertical joint or seam 11. The bottom is thereafter formed 45 by folding a marginal portion of the blank in the usual or any suitable or desirable manner. In view of the many common methods in which the paper may be folded to form the bottom of the container, it is believed to be unnecessary to 50 show any specific embodiment.

In order to render bag or package 10 impervious to air and moisture for the purpose of preserving the contents to be sealed therein, the side of the blank constituting the inner surface of the bag 55

is coated with a thin, dry film 12 of a thermoplastic lacquer having potential cementing qualities. As an example, said film may be composed of a nitro-cellulose lacquer having thermoplastic qualities, or for some purposes cellulose acetate may be advantageously employed. The lacquer or acetate film constitutes an impervious coating which will increase rather than impair the tensile strength of the fibrous material, and the adhesive qualities thereof may be utilized in the construction and sealing of the container, as will more fully appear hereafter. Lacquer film 12 is preferably constituted by a lacquer that may be activated or rendered tacky by a solvent, by heat, or by both, and when heat alone is used as an activating agent said lacquer should be rendered tacky only at temperatures considerably in excess of usual room temperatures, for example 130° to 150° F.

20 While lacquer coating or film 12 may be placed on the inner surface of bag 10 by means of a spray, for example, after the latter is formed in the usual or any well-known manner, it is preferable to apply the film to the surface of the blank before the same is folded to form a container of the desired shape. The cementing qualities of the lacquer may thus be utilized in the construction of the container to firmly and imperviously join the ends of the blank at seam 11 and bind the engaging surfaces of the bottom folds together. Heat and pressure may be applied at the desired points during the fabrication of the container by suitably heated die members for rendering the lacquer sufficiently tacky 35 to be pressed into the interstices of the overlapping or engaging fibrous surfaces and thereby form a strong, impervious bond between the same. The bond thus formed will not be weakened when the package is subjected to a wide variation of 40 room temperatures in any season, since the lacquer is affected only by comparatively high temperatures.

One suitable lacquer which may be employed to form the coating on the inner surface of container 10 is composed of about 65 percent of ester solvents, such as ethyl acetate, butyl acetate or the like, and such hydro-carbon as toluol, and about 35 percent of solids which can be readily activated by solvents as well as heat. The solids content is composed of about 25 percent of low viscosity nitro-cotton, 60 percent of resins and about 15 percent of a plasticizer such as dibutyl phthalate. The resins employed may contain some gums, such as ester gum, but usually synthetic resins which have more definite physical properties than any natural resin are used. This lacquer is free from tack at room temperatures and under normal conditions of humidity. Contact temperatures for forming seals at the overlapped portions of the blank from which container 10 is constructed must be in excess of 140° F., the excess being dependent upon the speed of operation and the conductivity of the materials used. The above lacquer is also adapted to harden quickly after activation and accordingly permits rapid operation of the sealing machinery.

It has been the practice heretofore, particularly in grocery stores and similar places of business, to fill uncoated paper packages or bags similar to the above and tie the same with cord or employ a separate adhesive coated strip to hold the closing folds of the open end in place. Much time is unnecessarily consumed in closing bags in this manner and the resulting closure

is not impervious to air and moisture and is subject to leakage. With the novel bag constructed in the manner above described, the open end thereof may be readily and quickly closed and bonded by an impervious seal after the desired 5 contents have been placed therein. The grocer or other merchant is thus enabled to package bulk foods and those which are apt to deteriorate when subjected to atmospheric conditions of temperature and humidity in an inexpensive, impervious package. Such articles, even though hygroscopic, may thus be packaged and retained 10 on the shelves for sale during an indefinite period without danger of deterioration.

In the embodiment of the invention illustrated 15 narrow strips 13 at the upper margins of two opposed sides 10a, 10a of the container are also coated with a thin, dry film of thermoplastic lacquer of the character above described. The open end of the container may thus be sealed by 20 merely pressing or folding the sides 10a, 10a of container 10 inwardly, as indicated by dotted lines in Fig. 2, thereby causing opposite ends of strips 13 to engage one another, and simultaneously pressing the inner coated surfaces of the 25 marginal edges of sides 10b, 10b, into engagement with each other in a manner which will be readily apparent from an inspection of the drawing.

It will be noted that in folding the upper 30 margins of sides 10a, 10a along the folding lines or creases a, b, which may be provided if desired, the edges of said sides drop below the upper edges of sides 10b, 10b. It will of course be understood that the thickness of the material from 35 which the bag 10 is fabricated is exaggerated in the drawing for the purpose of clarity. Heat and pressure sufficient to activate film 12, 13 are then simultaneously applied to the outer surfaces of the marginal portions of sides 10b to complete the seal, the heat activated adhesive 40 being pressed into the interstices of the paper to form an impervious bond. With the sides 10b entirely coated with thermoplastic lacquer, the closure seal may be made at any point throughout the length of the bag in case the latter is 45 not completely filled.

Novel portable apparatus suitable for use on the counter in a retail store is provided for forming the closure seal above described and for simultaneously producing indentations and complementary ridges constituting a line of severance adjacent said seam without impairing the impervious character thereof whereby the package may be readily and neatly opened for dispensing the contents thereof. In the illustrated form, 55 said apparatus comprises a stand 14 having a pair of axially spaced trunnions 15, 15 in which a shaft 16 is rotatably journaled. Keyed or otherwise suitably secured to said shaft between trunnions 15 is a handle 17. A U-shaped pressure 60 and heating member comprising a pair of arms 18, 18 having hub portions keyed to shaft 16 and a heating and pressing iron 19 joining the lower ends of said arms is adapted to be pivotally moved by handle 17 so that the inner surface of 65 said iron will move into parallel relationship and cooperate with the flat face of an iron 20 which is secured to a portion 22 mounted on stand 14 directly below trunnions 15.

Any suitable means may be provided for heating members 19 and 20 to desired temperatures, such means as shown being constituted by electric heating elements 21, one of which is removably inserted into an opening in member 19 and the other in an opening drilled in portion 22 ad- 75

jacent member 28. Elements 21 may be connected to any suitable source of electric current through leads 23.

In order that the bag may be readily opened after being sealed by the apparatus above described, a plurality of wedge shaped beads 24 (Fig. 5) may be provided in a horizontal interrupted line across the face of sealing iron 28 adjacent the lower edge thereof and a plurality of recesses 25 complementary to said beads are formed in the face of sealing iron 18 or vice versa. Thus, when the upper end of the bag 10, after the same is folded in the manner illustrated and above described, is held between parts 18 and 28 and pressure is applied by pressing downwardly on the outer end of handle 17, films 12 and 13 will be activated at the points of heat application, i. e., throughout the width of the container, and pressed into the interstices of the paper to form an impervious bond between the engaging surfaces. At the same time, through the cooperation of beads 24 and grooves 25, a line of indentations 26 (Fig. 2) is produced adjacent the lower edge of the seam, thereby forming a line of severance whereby the container may be readily opened. Since the pressure applied by beads 23 on one side of the seal is relieved by grooves 24 on the opposite side, it will be seen that the paper will not be ruptured nor the impervious character of the package impaired.

Any suitable means, such as coil springs 27, interposed between stand 14 and arms 18, may be provided for normally holding the faces of sealing irons 18 and 28 out of engagement. If desired, suitable cutting means may be provided adjacent the upper edges of members 18 and 28 for trimming any excess paper from the top of the container simultaneously with the making of the closure seam.

There is thus provided a novel, fibrous bag or package which may be readily and inexpensively manufactured and a novel method and means for constructing the same and sealing a commodity therein, whereby the latter will not only be protected from air and moisture outside the bag but will retain the moisture which is in the contents at the time of packing. A neat appearing package which may be readily opened is also thus provided.

Although only a single embodiment of the invention is illustrated and described in detail, it is to be expressly understood that the same is not limited thereto but that various changes may be made in the design and arrangement of parts, as well as in the size and shape of the bag illustrated, without departing from the spirit and scope of the invention, as will now be apparent to those skilled in the art. In certain instances it may be desirable to insert the bag of the present invention in a rigid container, such as a tin, to facilitate shipping and distribution of a product. In carrying out the method of the present invention, it may prove useful to

employ a solvent in addition to heat for cementing the vertical seam and bottom folds. The top seam, however, is preferably made by the application of heat only. The thermoplastic lacquer possesses characteristics such that the bags, prior to use, may be stored for long periods of time without any danger of the lacquer becoming tacky or that temperature changes will cause the parts to adhere one to the other, whereby the usefulness of the bags would be destroyed, as would be the case if common adhesives, such as animal or vegetable glue, were used to seal the bag. For a definition of the limits of the invention, reference will be had primarily to the appended claims.

What is claimed is:

1. The method of forming an end closure on a container having a mouth at one end thereof which consists in tucking the ends of said mouth inwardly and drawing the inner surface of the 20 sides of said mouth into contact with each other and with the inner surfaces of the tucked ends of said mouth, applying heat and pressure to activate a lacquer coating on said engaging surfaces to cement said surfaces together and form 25 an impervious seal across said mouth, and simultaneously impressing a plurality of aligned indentations in said sealed portion across the width of said container to provide a line of severance whereby the container may be readily 30 opened.

2. The method of closing an open ended container which includes coating the inner surface of the margin and two oppositely disposed portions of the outer surface of the margin at the 35 open end of the container with a thin, dry film of thermoplastic lacquer having potential adhesive qualities, tucking the double coated portions of the margin inwardly and simultaneously drawing the single coated portions of the margin into contact, applying heat and pressure to the engaging surfaces to activate said coating for adhesively securing said engaging surfaces together to form an impervious seal across said open end, and impressing a plurality of indentations and 40 complementary ribs across the width of said container to provide a line of severance whereby the same may be readily opened.

3. The method of forming an end closure on a paper container formed of flexible sheet material which consists in tucking the ends of the mouth of said container inwardly to thereby flatten the end of the container, applying heat and pressure to the margin of the flattened end to activate a dry coating of thermoplastic lacquer 55 on the engaging surfaces of said margin to adhesively secure said surfaces together and form an impervious seal across said mouth, and simultaneously impressing a plurality of aligned indentations and complementary ribs in said seal 60 to provide a line of severance for opening the container.

GEORGE ARLINGTON MOORE.
